TUBING ATTACHED REINFORCING
TRAPPING STRAINER

Ervin H. McClease, Bakersfield, Calif.

Application December 17, 1938, Serial No. 246,421

24 Claims. (Cl. 166—5)

This invention is a sand trapping, channel-forming, reinforcing strainer for deep well liners, or for sole use in hard well holes or wells without a first liner.

An object of the invention is to provide an apparatus to largely control or eliminate the entry of earthy solids from the well formation into the tapped portions of oil or water wells with the infiltration of the liquids from the formation.

Another object is to provide a strainer which will stabilize and center a gas anchor or a well tubing in its liner, and reduce vibration, and wear, and retard or stop crystallization of such parts.

A further purpose is to provide a substantial trapping reinforcement to give much added resistance to formation pressure, as from heaving, caving, shifting, and gas and fluid pressures, and to greatly reduce the hazard of collapsing or buckling of the main liner.

An additional object is to provide a sand trapping strainer which will give a substantially normal rate of flow from the well; that is will prevent complete sand bridging in the liner and will afford ample interstitial structure for the well liquids to maintain channels of normal flow volume. Especially it is an object to provide sub-passage-ways to enable the stream to move at a rate to carry along a suitable amount of solid particles from the formation to keep the formation orifices open for their normal flow in a manner not possible in liners in which the sand can pack or bridge as a seal to block the sometimes small spring orifices from which the fluids leave the formation at the face of the well bore. A fast moving liquid will act as a vehicle to lift the solids through the tubing foot to a level well above the spring face of the formation.

Also a purpose of the invention is to provide for the ready removal of the loaded, sand trapping strainer or reinforcement, as it may be called if used as a secondary device in the first or main liner, at such times as the well may determine without need of recourse to very costly and hazardous bailing operations with a special tool.

An important object of the invention is to provide means by which to receive and trap formation grains at about the level, in a formation face, from which they flow into the hole with the spring liquid, as oil or water, and also provide for the trapping of specimens of the products at their inflow level to provide a true level-indication formation tester at each period. the trapping strainer is pulled for clean-out, or, if desired, for formation test. More specifically, an object is

to provide elongate trapping means to obtain and show at the different levels the nature of the incoming well product or the lack of inflow, and to provide for keeping formation grains or suspended solids from settling to a lower level than at which they come in, and still provide for the ascent with the moving liquid of as much of the fine solids as is possible. In other words, an object is to provide a method and a means in the form of a sand trap and strainer and remover of a length equal to or greater than the depth of the tapped formation or producing zone in the well to obtain a faithful, production-level log or indicator for a given well.

15 It is a further object to provide a tubing-attached and handled strainer which may be readily activated from time to time to break up any small, local bridges tending to accrue at one or more formation levels along the installed trapping strainer. In this connection an object is to provide a tubing lowered, anchored and pulled trapping strainer; to provide a trapping strainer consisting of slack-jointed sections to successively stack on a main liner shoe or otherwise formed support and which sections will successively, from topmost downwardly, separate to a limited degree upwardly when the attached tube, or other well string to which the strainer is applied, is pulled either merely to open the section, relatively for bridge breaking, or for pulling the loaded stand of sections for formation testing or for well clean-out. Also, an object is to provide a variety of sections making up a strainer assembly, in which assembly the sections superpose in normally spaced relation and have provision for vertical travel of liquid and at the same time to entrap local level formation grains to keep a log.

40 An additional object is to provide for a brushing or wiping of the orifices of the main liner at the same time that the strainer sections are activated or jostled by vertical vibration to smash possible bridges.

45 This well liner orifice brushing or wiping function is also done when the strainer is pulled from the liner proper for any reason, or when it is set back into the main liner in telescoped operative position.

An object, also, is to provide a safety-joint, inner strainer combination, with a tubing especially, 50 or other appropriate string, so that in the event of the lower end of the string becoming sanded or jammed from any cause, the upper string and the associated strainer may be loosened off the lower part and used as a means to free the sand stuck part so that it would not be lost and could

be pulled from the hole. And a further object is to provide safety-break points along the inner strainer to enable recovery of as much apparatus as possible above collapsed or otherwise frozen bottom portion of the assembly.

The invention consists of certain advancements in this art as will be set forth in the ensuing disclosure and having, with the above, additional objects and advantages as hereinafter developed and whose construction, combination and details of means will be made manifest in the description of the herewith illustrative embodiments; it being understood that modifications, variations and adaptations may be resorted to within the spirit, scope and principle of the invention as is more directly claimed herebelow.

Figure 1 is an elevational axial section of the upper portion of the strainer assembly and

Figure 2 is a like section of its lower portion, both in a well liner; the assembly parts being in normal-flow, landed position on a liner shoe.

Figure 3 is a sectional plan of the coupling saddle ring on a tubing collar on line 3—3, Fig. 1.

Figure 4 is a cross-section of the coupling body on line 4—4, Fig. 1.

Figure 5 is a sectional plan of an upper cup unit of the assembly, showing associated connection parts in section on line 5—5, Fig. 1.

Figure 6 is a cross-section on line 6—6 of Fig. 2; showing attached, offset buckets.

Figure 7 is a detail broken elevation of a form of side-hang bucket.

Figure 8 is a sectional elevation of a nesting, modified form of trap bucket unit as being set into position.

Figure 9 is a top plan of Fig. 10, and

Figure 10 is a sectional elevation of a tube receiving cup unit with parts of hangers of a super-adjacent unit in lowering position.

A well casing L is shown as surrounding and extending below an adapter A carrying a lower reduced size liner Lx with wall perforation P, for any desired height, permitting formation flow into the liners above the bottom shoe S. As here adapted the strainer is mounted on a string of tubing T of any desired length, and the lower end of the tubing T being shown in Fig. 2 as positioned well above the shoe S to leave a space of any desired length in the liner Lx between the tubing and the shoe.

This space above the shoe tends to pack up with fine well solids and the present invention includes means attached to the tubing T to reduce or retard this packing tendency and also means to remove the sand pack, thereby cleaning the liner.

As here shown a top saddle ring 2 is fitted on the tubing to seat downwardly on its lowermost collar C. Slidably mounted in this saddle is a set of coupling rods 3 slidably passing through a washer 4 which is thrust upwardly against collar C by strong springs 5 on rods 3.

The rods 3 are solidly fixed by nuts 6 to the upper flange 7 of a coupling sleeve or body 8 slidably fitting around the given inserted tubing T. To the lower end of the body 8 there is firmly attached, as by bolt-shanks 9, a suitable packer 10, of any well known and adaptable construction which serves to seal off the casing L and space thereabove about the tubing T. The packer 10 preferably has downwardly opening valves 11 to prevent a vacuum being formed below the packer in a well being pumped.

Another important function of the downward by-pass valves 11 in the packer 10, is to provide for the washing of each receptacle unit as the

units are successively picked up from collapsed or stacked position to extended position.

The object of the washing process is to clear the cup-like units of any packed solid or semi-solid materials, which may be about their inner or outer sides.

Now in some cases, wells may have a very low fluid level, and for this reason there will be no fluid above the packer 10. In such wells, the fluid should be supplied from some outside source. That is, the fluid should be dumped or pumped in at the well head, within the well casing L but outside the tubing T. Since the object of the fluid washing is to eliminate friction about the sides of the various strainer units, a lubricating fluid should be used for this purpose. In water wells or oil wells which produce a great deal of free water, it would be ideal if a lubricating fluid of a greater density could be used for this purpose.

The tubing below the seal level is perforated for fluid intake in the usual manner and all fluid from formation rises in the liner Lx and casing L and passes into the tubing.

The means to trap formation grains and provide flow channels includes divers forms of cups or traps. Above the adapter A, and below the packer 10, there is considerable annular space about the tubing T and this space is reduced in diameter as it extends into the lesser bore of the well liner Lx. Below the packer a plurality of trap units 15 is provided each having an outer cup wall 16 quite loosely fitting in the casing L to leave an annular flow channel 17 at the adjacent bore surface of the casing, and each unit is provided with an inner concentric wall 18 loosely slideable about the pump-tubing T to provide for fluid flow thereabout. There is thus formed an annular sand pocket 19 in the cup between the walls 16 and 18.

Various telescopic or slideable means may be provided to afford attachment between the top unit 15 and the superjacent packer 10 or such other device as may be associated in the string set-up, and as here shown the lower element of the packer has a series of parallel, depending shanks 20 preferably tubular to provide up-flow ducts 21 for fluid which may accumulate in the next lower cup unit. The wall structure 16 and 18 of each cup device as 15 or others so desired, is vertically slotted at 22 to receive a hitch device such as a radial cross pin or screw 23 passing through a relative intruded shank 20 from the bottom of the next upper element as packer 10. These cup units have like shanks 24 likewise hitched by pins 23 to next lower cups in the assembly, in which there may be any desired number of cups under the set packer 10. There is thus provided a lost motion or slack type of hitch or connection by the pins 23 and slots 22 in walls of the several cups 15 and the packer.

While the cup string is being lowered into the well with the assembly hung by the saddle ring 2 on collar C on the tubing T, the cups are in open or spaced position in relation to each other and suspended from the tops of their slots 22 on the cross pins or, screws 23 of the next higher string element. When the assembly is landed or bottomed, as later set forth, the cups close down on each other to a degree determined by the length of the slack slots 22; the top edges of the various cups being suitably vertically spaced from the bottom of the next higher element.

When the assembly is bottomed on a given foot

rest as the shoe S or formation the cups come successively to rest on each other and the tubing gradually descends through the arrested elements until the packer with its connected body member 8 come to rest on the collapsed string of cups, and the springs 5 which provide a desired cushion reaction to the tubing setting on the washer 4 are compressed; the rods 3 sliding up in the saddle ring 2 during such relative downward movement of the tubing.

A second important function of the assembled coupling device, consisting of saddle ring 2, coupling rods 3, washer 4, springs 5, nuts 6, upper-flange 7, body 8, and bolt shanks 9, is to provide a vertical play of considerable length between body 8 and saddle 2 to allow for the placing of all cup units in collapsed position; to yieldably hold them so placed, and to have sufficient up and down slack to allow for the setting of a tubing catcher.

To further explain this function, an operator is running a completely assembled strainer into a well on a string of tubing T. Now in time the bushing 36 seats within the well liner shoe S; next, the anchor block 34 settles into place, after which each higher cup unit or other element is in turn lowered or collapsed into standing or arrested position; then eventually the packer 10 settles to the stack of arrested parts. Now at the time the packer is arrested the operator continues to lower the tubing string thereby compressing the springs 5, until they are completely compressed, at which time the tubing string begins to apply some dead weight to the coupling device 8, packer 10, and all units and assembly sections thereunder. Now at this time, the operator at the well head, notes this loss of weight on the weight indicator, and naturally assumes that the complete strainer assembly is bottomed, collapsed and properly in functioning position. However the tubing catcher is not yet set. Assuming that the operator knows that there is three feet difference between the fully compressed and fully extended positions of the springs 5, he proceeds to set the tubing catcher, by raising the tubing approximately 34 inches, then dropping it sharply two feet or other required amount extra. This two feet drop sets the tubing catcher simultaneously, without disturbing any of the lower strainer assembly, which is already in operative position.

Note that in the position of parts as just described there is no dead weight of the tubing T applied to any part of the assembly below the springs 5, that the springs lack approximately ten inches of being fully compressed, that the springs 5 exert a powerful downward pressure on the packer 10 and all lower units of the strainer, thereby holding these parts in their collapsed position, despite the upsurge of liquids and gas tending to raise them. In the position of parts are described just above, the foot end of the tubing T will not rest in its cup seat 27, but will hang approximately ten inches above it.

At this point it may be explained that should the tubing or other string in its stead below the collar C become frozen or trapped in the well hole it is an important feature of this invention that the lower tubing string may be disconnected at the collar C to enable all of the tubing string above and connected to the upper end of the collar to be lifted, to successively pull up one cup 15 after the other with the purpose of breaking up a sand pack that may have formed and be holding the tubing section extending from the lower end

of the collar. To provide for the disconnection of the collar C from the tubing section in the lower end of the collar such lower end is provided with a left hand thread 25 to take a like thread on the upper end of the inserted, next lower tubing section. It is only necessary therefore to give the upper string of tubing several right hand turns in order to unscrew thread joint at 25 and permit the upper string to be gradually lifted to successively pick up the hitched cups 15, and other hitched parts therebelow. When the upper tubing and the attached strainer assembly are lifted the separate, slackly hitched strainer members are, from the top downwardly, successively lifted along the lower frozen tubing until the frozen part is entirely free, whereupon it is engaged and lifted by the seat 27.

This may be repeated until the sand bridge or bridges are opened up either to re-establish well flow, or as suggested, to free the stuck tubing foot section if possible. If it is thus freed, the distended assembly can be pulled by the upper string of tubing and bring with it the fished part of the lower tubing; thus the assembly of trapping units becomes a practical fishing tool.

Somewhat above the level of the adapter A the cup units are of a reduced outside diameter so that they may be extended down in a collapsed stack of suitable length into the reducing adapter bore; the reduced cups being indicated at 15'.

As shown in Fig. 5 the annular space of the cups 15-15' may be provided with small wells 26 about each of the hitching shanks 24 so as to provide an up-flow channel from and around each shank.

These wells 26 and tubular shanks 24 are preferably perforated with minute or pin sized holes 24', so as to form sub-upflow channels for liquids, gas and only the smallest of grains of sand, silt and other solid materials. Such perforations are shown in the tubular shanks 24 and wells 45 of Fig. 10.

These separate sub-passages will continue to receive liquids, gas and small solid particles long after all larger outside spaces of the strainer and well liner have become bridged and choked off by the coarse sands, shales and gravel often entering a well liner. With the greater area of the strainer flow space closed, and the sub-passages 24' taking the flow, it is readily seen that the flow through the reduced sub-passages will be greatly speeded up. This speeding up action, through the sub-passages, creates an up-flow pressure against which the small solid particles are not liable to bridge over. Thus a well may produce gas and oil through the strainer sub-passages for weeks or months after it has otherwise bridged over; and would have been off of production but for the flow through the sub-channels.

Another function of this strainer is its tendency to conserve gas, in fluid and gas producing wells, and at the same time raise the normal fluid level of the well. This function is accomplished by the strainer greatly reducing the flow area upward through the well liner proper. This reduction of the flow area causes a given amount of gas to lift a greater amount of oil or other liquid up to a given point or to a higher point in a well. In other words it causes an increase in the ratio of oil to gas raised to the point where it enters the gas anchor or other perforated tubing.

This liquid raising function is obviously still more pronounced when the flow is further re-

stricted to the sub-channels as previously explained. The speeding up of the sub-passage stream, causes the gas to boost the liquid ahead of it, instead of breaking through the liquid and dissipating itself in large bubbles as it would in a large slow moving stream.

The lowermost of the adapter string or stack of cups 15' is provided with a seat or socket 27 to receive the point of the tubing, and if the upper string is pulled up as a fishing tool as above described, the foot end of the tube will stand on the cup seat 27 as in Fig. 2, which is provided with ascent ducts 28 for flow upward into the duct 21 and well 26 of the strainer unit 15.

There may be provided at any suitable point in the assembly a means to brush or wipe the adjacent bore surface of the casing or liner Lx, and such means here includes a circular brush device 29 attached by pins or bolts 30 to a crossed arm 31 which is hitched to the next cup 15' as by tubular shanks 24, as above.

This function of brushing the well liner and its slotted perforations might be as well accomplished by constructing any of the strainer elements with a considerably reduced diameter, then studding the outer walls with numerous stiff wires for brushing, thus forming a combined brush and cup unit.

Since the part of the liner Lx below the foot of the tubing T is unobstructed, above the shoe S other forms of stacking, sand trap cup devices may be employed. One such form is shown in Figs. 2, 6 and 7, as being a semicylindrical element 32 designed to loosely circumferentially fit the bore of the liner Lx. A series of these "half" cups is built up to given length and their contiguous corners are aligned with the cups in alternately staggered relation to form staggered open spaces O on each side of the axis of the strainer assembly. These half cups are slidably mounted, on one side of the assembly, on corner pins or bolts 33, fixed in the corners of the half cups on the opposite side of the string or assembly.

Below the lowermost cup element 32 there is attached thereto an anchor block 34, the connection being made as by a slack hitch or sliding pin or bolt means 35 which allows the next above parts to settle at rest on the anchor. This anchor is in turn slackly connected to a bottoming guide or bushing 36 by a pin or bolt 37.

When the made-up, strainer assembly, in the form for instance as above set forth, is lowered and set in a well with and by means of the pump tubing T, the bushing 36 finally comes to rest and centers on the liner shoe S and then all of the slackly hitched elements of the assembly settle one after the other on each other. They center the tubing and steady it, and they constitute a firm reinforcement for the surrounding liner means Lx and casing L or a naked formation well. The function of breaking and scattering packs of well solids or bridges (which may have formed below the bottom of the upper tubing T) may be accomplished by lifting the upper tubing T and the attached strainers until the assembly is fully extended and slightly lifted from the well bottom. However, if such sand packs or bridges are formed along and about the lower tubing T it may be frozen and unpullable. If this is the condition it will be necessary to disconnect the upper tubing T from the lower tubing at the joint 25 and vertically move the upper tubing T whereby to effectively separate the said strainers and shift them along the lower tubing thereby freeing the lower tubing T and breaking the sand bridges along the assembly. The sev-

eral pockets of the elements serve to catch solid grains in the liquid well product.

This function of breaking up packs of solid materials and sand bridges in a well, can obviously be accomplished without first unscrewing the left hand threaded tubing collar 25 from the lower element of the tubing T, in all cases where the solid and semi-solid materials are packed, and bridged in the well liner and strainer, below the foot of tubing T. In such cases the tubing is left free and clear of all binding influences and can be raised as one unit. Then, as each receptacle unit is moved, it breaks up the surrounding bridge, scattering it downward by gravity, or scattering it upward by combined gas and liquid force; and also a portion of the finer solids of the packs and bridges are taken into the sub-passages and carried by the way of these passages and the well tubing to the head of the well, and thence out.

Naturally, after a successful bridge breaking operation, the tubing, the strainer and all parts carrying production, may be re-set in their normal flow position and the well put on production, with its normal flow re-established.

This bridge scattering operation can be repeated from time to time as necessary until such time as it is found to be ineffective; in which case, the strainer should be pulled from the well, dumped, cleaned, inspected, repaired if necessary, then reset as previously explained.

At this point it is appropriate to describe the pulling of a tubing attached strainer. To render the description of this pulling operation more comprehensible it may be assumed that in this case the tubing T is free and clear from sand packs, bridges, or any other binding force. Also assume that each receptacle unit or other unit below the packer 10 has a one inch slack space from its fully telescoped position to its fully extended position and that said units are resting in their fully telescoped position.

Now in the actual operation of pulling the tubing and strainer assembly, the operator at the well head prepares for tube pulling in the usual manner, then begins to lift the tubing with a steady slow motion. When he moves the tubing at the well head, the entire string of tubing to its very bottom moves as a unit. Now as the tubing is moved upward, the saddle ring 2, the washer 4 and the top of springs 5 move in exact unison. As yet there has been no movement of the lower parts of the coupling device, the packer, or any part of assembly below the packer. Upon further movement upward of the tubing string, the springs 5 become fully extended, at which time the saddle ring 2 contacts upper nuts 6'. This contact sets in motion the upper nuts 6', the rods 3, and all parts of the coupling device down to and including the packer 10 and shanks 20. Now with the entire string of tubing, all parts of the coupling device and the packer in free upward motion, no parts of lower assembly have as yet been moved. However, upon a further upward movement of one (1) inch, the top-most cup-like unit 15 is contacted and set in an upward motion. Another one (1) inch upward motion picks up a second cup-like unit and so this action continues, each successive one (1) inch upward motion, picking up another unit, until at last the bottom bushing unit 36 is picked up and set in upward motion. Since these units are liquid washed as they are successively picked up, it may be assumed that they are fairly free from friction, once they are all in motion and the

operator may speed up the lifting motion and proceed as with a normal tube pulling job.

In Fig. 8 there is shown a form of flower-pot shaped traps or cups 15" to telescopically close into one another when the assembly is bottomed. In this adaptation radial pins or screws 40 extend from the lower ends of the pots or cups 15" into hitch slots 41 in opposite walls of next lower cups 15". Any of the several forms of trapping cups shown may be provided with side wall orifices 42 for fluid flow into the cups. The tapered form or pot shaped cups 15" give a larger side clearance than the cylindrical forms, enable faster up-flow and also are easier to break away if bridges should form.

In large diameter well holes a more capacious cup element may be utilized, and in Figs. 9 and 10 the shank wells are shown as separate cylinders 45 around which the well product may settle or flow in the cup chamber.

If desired the connecting pins 23 or the shanks 24 may be made of differential breaking strength at levels along the assembly so that should sections or trapping elements thereof be stuck due to liner collapse and not pullable, then only that portion of the sections below the topmost frozen section would be lost since the next above weakest connection point would shear or break and allow the upper assembly, that is the free portion, to be recovered by pulling the tubing string.

In reference to the units of this device variously referred to as "cup-like," "flower-pot shape," and "semicylindrical"—each of these different types may be considered as a special design to serve a special purpose in a well liner or well production zone. The special function of each type has previously been fully described.

However, these four different types of units are of two distinct models.

The first model is so shaped as to fit the well liner proper or casing, and to surround and fit the well tubing. It will hereafter be referred to as a "washer" model.

The second model fits the main well liner or casing with no provision made for passing the tubing through it, and will be referred to as a "disk" model.

In further reference to the packer 10, as shown and previously described as a part of the assembled strainer, it may be said that the prime object of this packer is—a safety device to protect the coupling assembly immediately above and also the tubing string above.

It can be readily understood that if a well should "heave," a considerable column of foreign material above the coupling assembly and about the well tubing, these parts and all lower parts would be "frozen" and unpullable.

In wells not likely to heave the packer 10 may be entirely dispensed with, but more telescopic strainer units must be added to bring the coupling device to a point safely above the possibility of a sand pack.

The special function of the tubing attached strainer, to act as a fishing tool by freeing and recovering a sand-packed and "frozen" gas anchor, or any part of the tubing below the packer 10, is of much importance, because there are a great many oil wells which have a very low fluid level—100 feet or less. These same wells may occasionally "heave" foreign material into the well liner and casing, to a height of 500 feet or more. Since a gas anchor or other perforated tubing must be extended within the oil, in order to pump oil, and, since it is obviously unsafe to

run the tubing below a point less than 500 feet from bottom in such a well—these sorts of wells are usually abandoned.

By using the strainer assembly as here shown and described, with the packer 10 and about 100 feet of units surrounding the tubing in their closed position, the owner or operator of such wells may safely run the well tubing within a few inches of the well bottom, if he so wishes. In this particular case, the socket unit 27 is placed in the assembled strainer just above the bottom bushing 36, and while any type or types of units or elements may be used at all higher points, they must be constructed as "washer" models.

In an opposite situation—with a well having a very high fluid level, the tubing can be correspondingly raised in relation to all other parts of the strainer. This may be worked out by using only a short tubing or gas anchor bull-plug below the lowermost collar C. The length of the bull-plug so measured that only the lower few inches will extend below the packer 10, when the complete strainer assembly is in its closed position. In this case, only the few inches of the bull-plug extending below the packer will be perforated. This arrangement naturally eliminates the possibility of any tubing becoming sand-packed or frozen. Therefore, the socket unit 27, may be dispensed with and also the left hand thread 25. Only disk model units or elements of any type or types would be used in this particular arrangement.

In those cases where 100 feet or more tubing is passed through the variously assembled strainer units, it is advisable to use the flush-joint tubing exclusively below the lowermost collar C.

In case no packer is used as a part of the strainer assembly, and no tubing catcher is used anywhere along the tubing string, any suitable coupling may be used between the upper tubing and the strainer assembly. In this instance, a reasonable amount of the tubing dead weight may be applied to the coupling device and all assembled units below.

Among novel features and advantages of this device as a well sand receiver, retainer and remover are: that it may simultaneously trap sand from all well levels along the length of the assembly; that being a pullable device it may safely hold trapped solids over a long period of time without pulling; that it traps well solids laterally adjacent to their point of entry and retains the solids as separate samples; that it de-sands a well by removing practically all trapped solids by the simple, safe and fast operation of pulling the well tubing and the attached assembly and that its use requires the use of no additional well tools or equipment.

It is well to bear in mind that the tubing attached strainer is, in its practical application to a producing well, of a permanent or semi-permanent nature. It may remain in operative position in a well for months, years or possibly for the life of the well. In this respect it differs radically from the many single function tools and devices used in fluid well production—most such tools and devices being used only temporarily.

Many oil wells have one or more sections of blank or imperforate pipe, topping on their perforated well liners. Such blank pipe is the same O. D. and I. D. as the perforated sections and have the adapter A screwed on at their extreme top.

In wells so lined, it would be permissible to

make the assembled coupling device, packer 10 and cup units 15, as here shown, of a reduced diameter, to fit the blank pipe. With this change made, the entire strainer assembly may be moved into the blank pipe and liner.

It is not the intention of this invention, as conceived, to be limited to the exact arrangement and position of the various elements 15', 27, 29, 32 and others as shown.

They are rather considered as interchangeable, 10 to be placed in a strainer assembly, singly, or in any combination of two or more types.

It is also conceived to construct either of the four types, as a "washer" model or as a "disk" model as well. When thus constructed any given 15 type may be positioned at any point within a well or well liner, regardless of the low or high position of the attached tubing.

For the purpose of running two or more types and models in combination, a suitable slack 20 jointed adapter may be designed to attach any given unit to any other model or type of unit.

As here shown and described, all strainer units or elements except the semi-cylindrical unit 32 are shown as having two slideable fastening devices and sub-flow passages combined. It is obvious that these units may be constructed with three or more such fastening devices. The object of such construction is to give greater lifting strength and better balance to the units.

The idea is also conceived, to so arrange the slideable fastening devices of all the various types and models of strainer units, so that they will stack in contact with each other, leaving no space between.

The semi-cylindrical type unit 32, may also be supplied with a sub-channel similar to other units, but located at its axis and separate from its slideable fastening devices.

Also with the exception of unit 32, any other 40 type of unit made as a "disk" model may be equipped with one combined sub-channel and fastening device at its axis.

The broadest possible conception of this invention, as practically applied to producing fluid wells, with its many functions and adaptations, would be to consider it as a new system of controlling the fluid, solid and semi-solid and gas 45 production of a well.

It is considered within the spirit and scope of this invention to use all the many variations, 50 adaptations, combinations and modifications as previously shown and explained, to dispense with certain parts as described and to use any suitable material in the construction of these and other parts.

In those cases in which a well has a heaving and caving condition only in upper part of the primary liner, a false well bottom may be created in combination with the tubing and the assembly 60 of strainer elements by use of a conventional bridge as used in cementing with a bailer.

What is claimed is:

1. A device of the class described, including a series of sand trapping elements connected together by slack joints for relative end motion in an elongate assembly and having interstices for fluid flow, and means for attaching the head of the assembly to a well tubing for lowering and pulling and for occasional reciprocative separation of the connected elements while in situ to break up sand bridges without pulling a well tubing and the assembly when attached.

2. A de-sanding apparatus for a flowing or pumping well, including a collapsible and ex- 75

tensible assembly of sand trapping bowls connected by slack joint connections endwise thereof.

3. The combination comprising a desired string of tubing, an assembly of slack jointed sand trapping elements, means for attaching the head of the assembly to the string for local vibration of the bottomed assembly if and when sand bridged, and the tubing having a left-hand thread to break tubing joint at said attachment for use of the assembly as a fishing tool for the lower part of the disconnected string.

4. A direct or auxiliary well re-inforcing device comprising a series of cup sections movably attached one to another to be installed as a unit in a naked or lined well for permanent or temporary production function; said cup sections including tube-like, interengaging channels to form a continuous, reduced, fluid conduit throughout the device.

5. In a well strainer and formation materials trap, a connected series of flower-pot shaped elements telescopic in a well bore or its liner and relatively telescopic one in another.

6. A well strainer to telescopically receive a sectional, separable tubing and including movably connected sections in train along the tubing and means for attaching the strainer to the tubing; said attached strainer having means to engage a frozen section of the tubing to free and recover said "frozen" section of the tubing when the latter is disconnected from an upper section of the sectional tubing.

7. A liner or well wall reinforcing strainer for a well hole, including an assembly of slack jointed strainer elements, and means for attaching the assembly to a tubular part or string for production installation and pulling thereby; the said elements relatively closing in stack arrangement when taking a seat on an obstruction.

8. Well apparatus for lining a bore face as a reinforcement, including an assembly of aligned or coaxial strainer elements for use with a given string, hitch means connecting the elements for axial slackness and for stacking when set in a well and means for attaching the upper end of the assembly to a given section of the string for lowering and pulling operations with and by the string, and for production set with and by the string; and said assembly including an element to form a seat for the lower end of the string, when the apparatus is to be used as a fishing tool to recover said lower end of the string.

9. A well bore or well liner strainer of a length to extend from the bottom of the producing zone of a well to a given higher level; the strainer including a series of relatively, collapsible, differentiated, relatively movably attached sections in suitable kind arrangement and including sections having sub-flow channels having restrictive flow orifices.

10. A strainer for the producing zone of a well, including a device attachable to a well tubing to support the strainer, and a packer connected to the lower end of the device, and said strainer including a plurality of slackly connected strainer elements suspended from said packer to strain well fluid to the tubing.

11. In a well strainer and desander, a tubing handled assembly including a plurality of slackly articulated trapping strainers to be installed and operative to catch sand in the producing zone of a well and whereby the well may be desanded in one operation by pulling the tubing and strainer at any time in one handling operation.

12. For well producing, a tubing having an attached assembly comprising a series of non-telescopic, separate, movably connected straining and trapping units.

13. In combination, for well production duty, a tubing string extending from the well head to any level within the well, a collapsible and extensible, sectional strainer and sand trapping device; said device including units telescopic along and each girdling the lower portion of the tubing, other units extending below the tubing and stacking on the well bottom, and means by which the tubing is secured to the device at the point of entry of the tubing into the device.

14. A well strainer for cooperation with a conventional well tubing, and means for coupling the strainer to a given tubing, said means including a coupling which is collapsible and extensible endwise and including an endwise expansion spring, and the strainer including a series of straining and trapping elements, and couplings connecting said elements for limited sliding, end motion.

15. An apparatus for producing wells, comprising the combination of a tubing attached, loosely-linked section, sand trapping strainer assembly, and a well packer telescopic on the tubing above the strainer and forming a connective unit for the strainer and the tubing and whereby well formation solids from below the assembly are prevented from heaving above the packer and into the space between the tubing and an imperforate well pipe, or a well wall, when the apparatus is in a well.

16. The combination comprising a well tubing having a packer telescopic thereon, means to connect the packer to the tubing, a chain-like assembly of slackly connected, sand receiving strainer units suspended below the packer, and the packer forming a baffling means to retain well solids below the packer level when the combination is operative in a producing well, and said packer having a downwardly opening valve means to allow downward drainage of well fluids when the combination is operative within or is being pulled from a producing well.

17. A well formation testing or sampling device including a plurality of separate, relatively movable, suspended sand traps which will, when installed in a producing well, each receive and retain samples of well solids coming from the laterally adjacent well level at which it stands; the trapped samples showing the formation along the device when the device is pulled and inspected.

18. In a sand trapping and desanding apparatus for producing wells, an assembly of separate sand traps each of a semi-cylindrical form.

19. A pullable well apparatus including slackly connected sections in an assembly of suitable length for the producing zone of a given well, the assembly being collapsible and extensible throughout its length, and said sections being of a pullable length; the apparatus being installable, in a well, in collapsed position; whereby when the apparatus is later engaged from the top and lifted, the sections are in succession adapted to be broken away from the binding influence of engaged solids and the unitary apparatus is pullable as a whole without resort to fishing operations.

20. A pullable well tubing having a non-rigid, sectional well apparatus including a series of slackly articulated, sand trapping strainers to be installed in closed relation in a well, and later to be pulled by the tubing to separately break the top and each succeeding strainer from a sand pack, if any; whereby the apparatus is pullable intact and without injury in extremely extensive lengths of the apparatus.

21. A pullable well producing structure composed of pullable, slackly linked sections and being pullable to a greater degree and pullable in longer lengths than other known well producing structures; said sections operating to facilitate such pullability.

22. In a device of the class described, an assembly of slackly hitched strainers.

23. Apparatus for a well, comprising the combination of: a well tubing terminating in perforated, lower sections, means for attaching the perforated tubing sections to the upper part of the tubing and being detachable by manipulating the upper tubing at the well head when the lower tubing is immovable, an elongate coupling body secured to the tubing above and extending below said means; said coupling body being endwise collapsible and extensible and having an endwise expanding spring device, a well packer secured to the lower part of said body and telescoping about the lower tubing and having downwardly opening, self-closing valves, and a series of loosely linked, fluid straining elements carried by and below the packer.

24. A combined strainer and trapping device for wells including a chain of slackly connected sand receiving cups having parts which are perforated for infiltration of well fluid.
